(57) CLAIM

The ornamental design for a wall mountable support, as shown and described.

DESCRIPTION

In a preferred embodiment, the nature of this product is a wall mountable support, such as a single or double rung towel bar, a single or double ledge shelf, or a mirrored shelf.

FIG. 1 is a left, top, front perspective view of a wall mountable support according to our new design;

FIG. 2 is a left side elevational view thereof, the right side elevational view thereof being a mirror image of the left side shown;

FIG. 3 is a top plan view thereof;

FIG. 4 is a bottom plan view thereof;

FIG. 5 is a front elevational view thereof;

FIG. 6 is a rear elevational view thereof;

FIG. 7 is a left, top, front perspective view of a wall mountable support according to another embodiment of our new design, the front and rear elevational views thereof being identical to respective FIGS. 5 and 6;

FIG. 8 is a left side elevational view thereof, the right side elevational view thereof being a mirror image of the left side shown;

FIG. 9 is a top plan view hereof; and,

FIG. 10 is a bottom plan view thereof.

The broken-line disclosure in the views is for illustrative purposes only and forms no part of the claimed design. The broken-away horizontal elements are understood to indicate unclaimed length.
